UNITED STATES PATENT OFFICE

2,436,343

DRUM SUPPORT FOR COMBINED WASHING
AND CENTRIFUGAL DRYING MACHINESEllsworth M. Wilson, Southport, Conn., assignor
to Remington Arms Company, Inc., Bridge-
port, Conn., a corporation of Delaware

Application December 21, 1944, Serial No. 569,163

10 Claims. (CL. 68—25)

1

This invention relates to washing machines, and particularly, to the type suitable for home or domestic use.

In the home type of machine, a receptacle for containing washing water and a basket or drum for holding the clothes are usually provided. The drum is rotated in such a manner as to cause the clothes to pass through the wash water, either for the actual washing part of the cycle or for a rinse portion of the cycle. After the washing has occurred and after the various rinses, the basket may be rotated at a higher rate of speed in order to centrifuge water out of the clothes. The clothes are usually located in the drum in such a manner as to be off center so that considerable vibration is set up in the machine during the wringing or centrifuging operation, and some of this may be transmitted through the casing into the floor or surrounding building.

One of the objects of this invention is to provide a mounting for the drum to provide for a gyratory motion during the wringing operation and to support the drum rigidly during the washing operation.

As will be explained hereafter, it also is desirable to lift the clothes out of the wash water tub during the wringing operation. These and other objects of the invention will become apparent from the drawings and description which are merely exemplary of the invention.

In the drawings—

Fig. 1 is a perspective view of one form of the invention, the casing and tub not being shown.

Fig. 2 is a diagrammatic sectional side view of the apparatus of Fig. 1 with a casing and tub indicated, the drum in this figure being shown in an upright or wringing position.

Fig. 3 is generally similar to Fig. 2, with the exception that the drum and support are shown in a washing position.

Fig. 4 shows a vertical view partly in section of a modification of the invention, the basket being shown in full lines in the wringing position and in dotted lines in the washing position.

Fig. 5 is a view of the lower guide support taken in the direction 5—5 of Figs. 4 and 7.

Fig. 6 is a top view of Fig. 4 taken along the line 6—6 of Fig. 4.

Fig. 7 is a fragmentary vertical view of a modification of the device shown in Fig. 4, there being an adjustable element for the shaft guide support.

Fig. 8 shows a device similar to Fig. 4, wherein the axis of the hinge is at a different angle than

2

that shown in Fig. 4, the drum in Fig. 8 being shown in its horizontal washing position.

Fig. 9 is a fragmentary view of a modification of the bracket of Fig. 4, showing adjustable elements for both the bracket and the hinge shaft guide support.

Fig. 10 is a fragmentary vertical view of a modification of the supporting means for the shaft guide support, the drum being in its wringing position.

Fig. 11 is similar to Fig. 10 with the drum in a washing position.

Fig. 12 is a fragmentary vertical view of a modification of the supporting means showing the pivot at a different angle than Fig. 4.

A frame 20 (Fig. 1) may carry pivot bearings 21 for pivotally mounting the shaft guide support or frame 24. Perforated washing drum or basket 22 with a closed bottom is mounted on rotatable drum shaft 23. The drum may be supported from shaft 22 by spider arm 26, or in any desired manner. C-shaped frame 24, having a top crossbar 19 and legs 11, 12, has a universal or flexible shaft bearing guide 25 for carrying the upper end of drum shaft 23. Crossbar 26 may have a keyhole-shaped aperture 27 or equivalent guide, spaced from the universal shaft bearing 25. Said keyhole-shaped aperture has a restricted portion 28 and an enlarged portion 29. There may be mounted on frame 24 a suitable motor drive 30 having a pulley 31, drive belt 32, and drum shaft pulley 33. The support of Fig. 1 may be placed in a container 34 (Fig. 2) having a suitable tub or water containing portion 35. The water may be fed to the tub automatically or by any suitable means, such as is well known in the art.

A hydraulic cylinder 36 of any suitable type having a piston rod 37 may be provided for moving the support on pivots 21. Another form of hydraulic cylinder is found in Figs. 2 and 3 at 38. A flexible connector 39 may be provided for pivotally operating the frame 24. The cylinder may be located along the vertical wall 38 of the container and the flexible connector carried around a suitable pulley 39 in any desired manner. It is apparent that other equivalent operating means can be used for pivoting the shaft guide support 24.

In order to wash clothes, they are placed in the drum 22 and the frame 24 rotated to the inclined position shown in Fig. 3 so that clothes in the drum 22 will pass into the water in the tub 35. The shaft, when in this position, will pivot about the universal bearing 25 and fall into

the restricted portion 28 of the keyhole-shaped aperture 27, and thus rigidly be held for the washing operation. Upon completion of the washing operation, the hydraulic cylinder 36 may be operated in any desired manner to rotate frame 34 to the vertical position shown in Fig. 2. When in this position, the basket can be rotated for wringing or centrifuging purposes. The motor 30, as is well understood in the art, may be of a multiple speed or transmission type so that it may be operated at a sufficiently high speed when in a vertical position to wring the water properly out of the clothes. The control of the various operations of the motor, pivoting of the guide support, and supply and withdrawal of the water may be accomplished manually or may be done automatically in any conventional manner, as is well known in the art. In washing clothes, it has been found that if the water is withdrawn from the tub while the drum is still rotating therein that some of the dirt may be redeposited in the fabric. If the drum is moved out of the water upon completion of the washing cycle, the water will drain from the clothes and much of the dirt otherwise deposited in the clothes will be eliminated.

In Fig. 4, a modification of the drum support is shown wherein a container or casing 40 may be provided and mounted on casters 41. A water container or tub 42 is carried in the container, inlet and outlet pipes 13 and 14 being provided. A door 43 can be placed in the container for access to the rotatable drum 44, although it is apparent that this door may be located in other parts of the casing. Drum shaft 45 is carried in the universal or flexible shaft bearing 46 mounted in bracket 47 of the shaft guide support 48. Spaced from the universal guide 46 is a second or lower guide 49. This guide may be a keyhole-shaped aperture 60 or equivalent guide having a restricted portion 51 and enlarged portion 52 (Fig. 5). The guide support 48 is hinged at 53 to a bracket 54 carried by casing 40. The axis of hinge 53 is inclined relative to the shaft 45. Mounted on the shaft guide support 48 is the driving motor 55, which may have a suitable reduction gear box 56. Pulley 57, drive belt 58, and shaft pulley 59 serve to drive drum 44 through shaft 45. Motor 55 may have any desirable speed control means for optionally driving the drum at wringing speed or at washing speed. In the position shown in Fig. 4, the drum is in the wringing position and the drum shaft 45 is located substantially centrally of the enlarged portion of the keyhole aperture so that the drum may have gyroscopic rotation about the universal bearing guide 46 during the wringing operation.

During the washing cycle, the guide support 48 is rotated about the hinge 53 to the position shown in dotted lines at 60. In this position, the drum shaft will fall into the restricted portion of the keyhole aperture and be held during the washing cycle. One method of shifting the shaft guide support 48 is by means of a gear 61 driven by a suitable control motor (not shown). This control motor can be connected to an automatic control switch in such a manner as to rotate the drum from one position to the other at an appropriate time. The control motor may also be operated manually, if desired. It is apparent that other means may be employed to move support 48 about the hinge axis.

Fig. 6 shows a top view of the apparatus of Fig. 4, the gear 61 being omitted therefrom. The 76

dotted lines 62 in Fig. 6 show the approximate lowered position of the drum.

The shaft guide support shown in the modification of Fig. 7 has adjustment means whereby shaft guide support 63 is fastened to hinge 64 by means of wing nuts 65, hinge 64 having arcuate elongated slots 66 to provide for adjustment, the other parts being numbered identically to Fig. 4.

In Fig. 8 is seen a guide support hinge arrangement wherein hinge 67 is placed at a slightly different angle than that of Fig. 4, so that the shaft 45 will be in a substantially horizontal position when the drum is in the washing position. The other details of Fig. 8 bear identical reference numerals as Fig. 4. It is to be noted that in Fig. 8 the shaft 45 is in the restricted portion of the keyhole aperture 49 so that it is held in the washing position. The belt 58 may be V-shaped so that it will track properly when the shaft is slightly out of line with pulley 57 because of movement of the shaft from the vertical to the restricted portion of the keyhole slot. In Fig. 8 the drive motor is arranged so that the belt tracks correctly when the drum is in the washing position, and in Figs. 4 and 7 is it shown as tracking correctly when the drum is in the vertical or wringing position.

Fig. 9 shows an arrangement similar to Figs. 4 and 8, with the exception that the bracket attachment to casing 40 is shown adjustable, there being wing nuts 68 and arcuate slots 69 similar to those on the shaft guide support itself. The remainder of the parts of Fig. 9 are similar to Fig. 7.

In Figs. 10 and 11, a modification of the means for shifting the shaft guide support of Fig. 1 is shown wherein the C-shaped frame 75 may be provided with suitable rollers 76 and 77, said rollers being guided in cam slots 78 and 79 carried by the casing 82. Rollers and cam slots may be provided on each side of the support. The shiftable guide support 75 may have a driving means 80 and drum 81 supported in a manner similar to the device of Fig. 1. The casing 82 may be provided with a water container 83 to hold the wash water. Any convenient means may be used for moving the shaft guide support 75 from the wringing position of Fig. 10 to the washing position of Fig. 11.

In Fig. 12, the pivot 53 is shown arranged at an angle of less than 45 degrees with the vertical, so that when the shiftable support is swung to a washing position, the drum shaft will be at an angle with the horizontal. The other details shown in this figure are the same as Fig. 4 and are given identical reference numerals.

The control means for the various parts of the cycle are not shown or described in detail in this application inasmuch as they do not form part of the invention. It is apparent that any suitable control device or sequence operator may be used to control the supply and withdrawal of water from the washing tub, movement of the shiftable shaft guide support, speed of the motor, etc., in the order desired.

What is claimed is:

1. In a machine of the character described, a drum; a rotatable drum shaft; a pivoted shaft guide support, said support being pivotable to move said drum from a substantially vertical wringing position to an inclined washing position; a flexible joint shaft guide carried by said guide support for guiding one portion of said shaft; and a second shaft guide carried by said

guide support, said second guide having formed therein an aperture with a restricted portion for supporting the shaft when the drum is in an inclined position and an enlarged portion communicating with said restricted portion for allowing gyratory rotation of the shaft when the drum is in a substantially vertical position, said restricted portion being below said enlarged portion when the drum is in an inclined position.

2. In a machine of the character described, a drum; a rotatable drum shaft; a pivoted shaft guide support, said support being pivotable to move said drum from a substantially vertical wringing position to an inclined washing position; a flexible joint shaft bearing carried by said guide support for guiding one portion of said shaft; and a second shaft guide carried by said guide support, said second guide having formed therein a keyhole-shaped aperture, the restricted portion of said keyhole aperture supporting the shaft when the drum is in an inclined position and the circular portion of the keyhole aperture allowing gyratory rotation of the shaft when the drum is in a substantially vertical position, said restricted portion being below said circular portion when the drum is in an inclined position.

3. In a machine of the character described, a drum; a rotatable drum shaft; a C-shaped pivoted shaft guide support having two legs and a top crossbar, said support being pivotable to move said drum from a substantially vertical wringing position to an inclined washing position; a flexible joint shaft bearing carried by the top crossbar of said C-shaped guide support for guiding one portion of said shaft; and a second shaft guide carried by a second crossbar located between the two legs of said C-shaped shaft guide support and spaced from the flexible joint shaft guide, said second guide having formed therein an aperture comprising a restricted portion for supporting the shaft when the drum is in an inclined position and an enlarged portion communicating with said restricted portion for allowing gyratory rotation of the shaft when the drum is in a substantially vertical position, said restricted portion being below said enlarged portion when the drum is in an inclined position.

4. In a machine of the character described, a container having a water tub in the bottom thereof; a drum; a rotatable drum shaft; a pivoted shaft guide support having a top portion, said support being pivotable to move said drum from a substantially vertical wringing position to an inclined washing position; a flexible joint shaft guide carried by the top portion of said pivoted shaft guide support for guiding one portion of said shaft; a second shaft guide spaced downwardly from said flexible joint shaft guide, said second shaft guide being carried by said guide support, said second guide having formed therein an aperture with a restricted portion for supporting the shaft when the drum is in an inclined position and an enlarged portion communicating with said restricted portion for allowing gyratory rotation of the shaft when the drum is in a substantially vertical position, said restricted portion being below said enlarged portion when the drum is in an inclined position; and pivoted means carried by said container for mounting said shaft guide support, said pivoted means being located so that the drum will pass through the water receptacle when the drum is moved to its inclined washing position.

5. In a machine of the character described, a container having a water tub in the bottom

thereof; a drum; a rotatable drum shaft; a C-shaped pivoted shaft guide support having two legs, a top crossbar, and a second crossbar spaced from said top crossbar, said support being pivotable to move said drum from a substantially vertical wringing position to an inclined washing position; a flexible joint shaft bearing carried by the top crossbar of said C-shaped guide support for guiding one portion of said shaft; a second shaft guide carried by said second crossbar, said second guide having formed therein an aperture with a restricted portion for supporting the shaft when the drum is in an inclined position and an enlarged portion communicating with said restricted portion for allowing gyratory rotation of the shaft when the drum is in a substantially vertical position, said restricted portion being below said enlarged portion when the drum is in an inclined position; and pivoted means carried by said container for mounting said shaft guide support, said pivoted means contacting the ends of the legs of said shaft guide support away from said crossbars and being located so that the drum will pass through the water receptacle when the drum is moved to its inclined washing position.

6. In a machine of the character described, a drum; a rotatable drum shaft; a pivoted shaft guide support, said pivot being on an inclined axis relative to said drum shaft, said guide support being shiftable to move said drum from a substantially vertical wringing position to an inclined washing position; a flexible joint shaft guide carried by said guide support for guiding one portion of said shaft; and a second shaft guide carried by said guide support between said flexible joint shaft guide and the drum, said second guide having formed therein an aperture with a restricted portion for supporting the shaft when the drum is in an inclined position and an enlarged portion communicating with said restricted portion for allowing gyratory rotation of the shaft when the drum is in a substantially vertical position, said restricted portion being below said enlarged portion when the drum is in an inclined position.

7. In a machine of the character described, a casing; a tub; a drum; a rotatable drum shaft; a bracket carried by said casing; a shaft guide support hinged to said bracket, the axis of said hinge being inclined relative to said drum shaft, said guide support being shiftable to move said drum from a substantially vertical wringing position to an inclined washing position, the drum in the washing position passing into the tub; a flexible joint shaft guide carried by said guide support for guiding one portion of said shaft; and a second shaft guide spaced from said flexible joint shaft guide and carried by said guide support between said flexible joint shaft guide and the drum, said second guide having formed therein an aperture with a restricted portion for supporting said shaft when the drum is in an inclined position and an enlarged portion communicating with said restricted portion for allowing gyratory rotation of said shaft when the drum is in a substantially vertical position, said restricted portion being below said enlarged portion when the drum is in an inclined position.

8. In a machine of the character described, a casing; a tub; a drum; a rotatable drum shaft; a bracket carried by said casing; a shaft guide support hinged to said bracket, the axis of said hinge being inclined relative to said drum shaft, said guide support being swingable about said

hinge axis to move said drum from a substantially vertical wringing position to an inclined washing position, the drum in the washing position passing into said tub; a flexible joint shaft guide carried by said guide support for guiding one portion of said shaft; and a second shaft guide spaced from said flexible joint shaft guide and carried by said guide support between said flexible joint shaft guide and the drum, said second guide having formed therein a keyhole-shaped aperture, the restricted portion of said keyhole aperture supporting the shaft when the drum is in an inclined position and the enlarged portion of the keyhole aperture allowing gyratory rotation of the shaft when the drum is in a substantially vertical position, said restricted portion being below the enlarged portion when the drum is in an inclined position.

9. In a machine of the character described, a casing; a drum; a rotatable drum shaft; a shiftable shaft guide support, said support being pivotable about a moving axis to move said drum from a substantially vertical wringing position to an inclined washing position; cam track guide means for carrying said guide support; a flexible joint shaft guide mounted on said guide support for guiding one portion of said shaft; and a second shaft guide carried by said guide support, said second guide having formed therein an aperture having a restricted portion for supporting the shaft when the drum is in an inclined position and an enlarged portion communicating with said restricted portion for guiding the shaft when the drum is in a substantially vertical position, said restricted portion being below the enlarged portion when the drum is in an inclined position.

10. In a machine of the character described, a casing; a tub; a drum; a rotatable drum shaft;

a bracket carried by said casing; a shaft guide support hinged to said bracket, the axis of said hinge being inclined relative to said drum shaft, said guide support being swingable about the axis of said hinge to move said drum from a substantially vertical wringing position to an inclined washing position, the drum in the washing position passing into the tub; adjustable means on said bracket to adjust said shaft axis; a flexible shaft joint guide carried by said guide support for guiding one portion of said shaft; and a second shaft guide spaced from said flexible joint guide and carried by said guide support between said flexible joint shaft and the drum, said second guide having means defining a keyhole-shaped aperture, the restricted portion of said keyhole aperture supporting the shaft when the drum is in an inclined position and the enlarged portion of the keyhole aperture allowing gyratory rotation of the shaft when the drum is in a substantially vertical position, said restricted portion being below the enlarged portion when the drum is in an inclined position.

ELLSWORTH M. WILSON.
